CLAIM

The ornamental design for the traffic cone, as shown and described.

DESCRIPTION

FIG. 1 is a perspective view of a traffic cone that emphasizes the front of the traffic cone.

FIG. 2 is a perspective view of the traffic cone that emphasizes the rear of the traffic cone.

FIG. 3 is a front view of the traffic cone.

FIG. 4 is a rear view of the traffic cone.

FIG. 5 is a left side view of the traffic cone, the right side view is a mirror image of the right side view; and,

FIG. 6 is a top view of the traffic cone.

The bottom view of the traffic cone forms no part of the claimed design.

The broken lines in the drawings are for illustrative purposes only and form no part of the claimed design.
